[57] **CLAIM**

I claim the ornamental design for a wall mounted lighting fixture, as shown and described.

DESCRIPTION

FIG. 1 is a perspective view of the wall mounted lighting fixture showing my new design;

FIG. 2 is a front elevational view of the wall mounted fixture;

FIG. 3 is a right side elevational view of the wall mounted lighting fixture, the left side elevational view being a mirror image;

FIG. 4 is a top plan view of the wall mounted lighting fixture; and,

FIG. 5. is a bottom plan view of the wall mounted lighting fixture.

The broken lines are shown in FIG. 1 for illustrative purposes only and form no part of the claimed design.
